ANTENNA

Filed Nov. 27, 1926

*Benjamin E. Banks,
INVENTOR
Victor J. Evans*

P. A. Hickey.

WITNESS:

UNITED STATES PATENT OFFICE

BENJAMIN E. BANKS, OF CHICAGO, ILLINOIS

ANTENNA

Application filed November 27, 1926. Serial No. 151,192.

This invention relates to certain novel improvements in an antenna for use in connection with radio apparatus and has for its principal object the provision of an improved 5 construction of this character which will be highly efficient in use and economical in manufacture.

A further object of the invention is to provide an antenna which is nondirectional, thus 10 being adapted for picking up ether waves traveling in horizontal as well as in vertical circles.

Other objects will appear hereinafter.

The invention consists in the novel combination and arrangement of parts to be hereinafter described and claimed.

The invention will be best understood by reference to the accompanying drawings, showing the preferred form of construction 20 and in which:

Fig. 1 is a side elevational view of the invention.

Fig. 2 is a top plan view of the same; and

Fig. 3 is an enlarged fragmentary side elevational view of the same.

In the drawing 10 indicates two spaced supporting standards between which my improved antenna 11 is adapted to be suspended.

The upper end portions 12 of the standards 30 10 are reduced to receive rings 13. These rings 13 have lateral extensions 14 which have connection through the medium of hooks 15 with insulators 16. Adjustably carried by the insulators 16 are eyelets 17 to which the end portions of the antenna are connected as at 17.

In the present instance, the antenna comprises a plurality of units 18 alternately disposed in horizontal and vertical planes. Each 40 of these units 18 comprise ring members 19 preferably formed of phosphorus bronze or brass. The ring members of the units are connected together by means of wire strands 20 and 21 preferably formed of non-corrosive material. The wire strands 20 have their end portions 22 connected to the ring members of the horizontal units and their intermediate portions 23 connected on opposite diametrical sides of the ring members 19 of the vertical units and their intermediate por-

tions 26 connected to opposite diametrical sides of the ring members 19 of the horizontal units as at 27. By this selective arrangement of the wire strands, the ring members will alternately be supported in a vertical 55 and horizontal plane and be prevented from twisting by action of the wind.

To tension the antenna the eyelets 17 are adjusted relatively to the insulators 16 until the antenna is properly tensioned. 60

From the above description it will be manifest that I provide an antenna which is nondirectional and which will be effective in use for picking up ether waves centering in a horizontal circle as well as those centering 65 about a vertical circle.

It will also be seen that I provide an antenna which can be manufactured at an economical cost.

While I have illustrated and described the 70 preferred form of construction for carrying my invention into effect, this is capable of variation and modification, without departing from the spirit of the invention. I, therefore, do not wish to be limited to the precise 75 details of construction set forth, but desire to avail myself of such variations and modifications as come within the scope of the appended claim.

Having thus described my invention what 80 I claim as new and desire to protect by Letters Patent is:

An antenna comprising a plurality of ring shaped units alternately arranged such that adjacent rings will extend at right angles to each other, means for conductively interconnecting said rings including securing means extended about alternate of said rings and connected at diametric points to juxtaposed rings, and connecting means extending between diametric points on said first named rings and points at which said first named connecting means are attached to said juxtaposed rings. 85 90 95

In testimony whereof I affix my signature. 95

BENJAMIN E. BANKS.
